(57) **CLAIM**

The ornamental design for a monitor display, as shown and described.

DESCRIPTION

FIG. 1 is a front elevational view of a monitor display showing my design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a reduced perspective view thereof.

FIG. 8 is a front elevational view of another embodiment of a monitor display showing my new design. The rest of the views of the embodiment of FIG. 8 are the same as those of the embodiment of FIG. 1, except for a perspective view thereof; and,

FIG. 9 is a bottom plan view of yet another embodiment of a monitor display showing my new design. The rest of the views of the embodiment of FIG. 9 is the same as those of the embodiment of FIG. 1.
